UNITED STATES PATENT OFFICE.

CARL M. WELTE, OF NEW YORK, N. Y., ASSIGNOR TO M. WELTE & SONS, INC., OF NEW YORK, N. Y., A CORPORATION OF NEW YORK.

CONTROLLER DEVICE FOR TRACKER-BOARDS.

1,158,015.

Specification of Letters Patent. Patented Oct. 26, 1915.

Application filed December 9, 1913. Serial No. 805,546.

To all whom it may concern:

Be it known that I, CARL M. WELTE, a citizen of the United States, and a resident of New York, in the county of New York and State of New York, have invented certain new and useful Improvements in Controller Devices for Tracker-Boards, of which the following is a full, clear, and exact description, whereby any one skilled in the art may make and use the same.

The invention relates to mechanical musical instruments and more particularly to the control of the tracker-board of such an instrument, that is, to devices for controlling the operativeness of the ducts or passages of a tracker-board with reference to the perforations of a music-sheet or roll.

In the ordinary type of mechanically operated musical instruments it has been common to employ a tracker-board over which a perforated sheet of music is passed and such devices ordinarily operate upon an exhaust principle so that atmospheric pressure admitted to the ducts of the tracker through the openings of the music roll as they come into registration with the respective tracker-ducts, release and actuate certain valve mechanisms which cause the sounding of the particular note corresponding to the tracker-duct which is released to the atmosphere. After such a roll has been passed over the tracker-board and the selection or selections of music represented thereon have been played, it is necessary to re-wind the roll and obviously, the tracker-ducts must be made inoperative with reference to the perforated sheet during this re-winding operation, otherwise the selections would be played backward. It has also become a general practice to utilize a plurality of tracker-boards with individually perforated music sheets for each tracker-board so that one roll or sheet of music may be played and during the re-winding of said roll, the second roll or sheet of music may be played. In such an arrangement, an instrument may be operated continuously.

The invention herein disclosed relates to the control of the tracker ducts and is designed to control the flow of air through the tracker ducts and connections so that the manipulation of the note-sounding devices may be controlled.

The object of the invention is to provide a simple and compact arrangement for opening and closing the ducts of a tracker with

reference to the sounding devices and a still further object is to control the ducts of a plurality of trackers.

It is also an object of the invention to provide an oscillatory or rotating device for connecting and controlling the tracker ducts which will condense the very numerous connections required into a minimum of space.

The invention, as illustrated in the drawing, is shown in connection with two distinct tracker-boards and their respective music rolls.

Referring to the drawings Figure 1 is a diagrammatic view of a pair of trackers and their connections to a player pneumatic. Fig. 2 is a detail view in side elevation of the controller device. Fig. 3 is an edge view of the device illustrated in Fig. 2, looking from the right of said figure with parts broken in section. Fig. 4 is a detail sectional view through the disks of the controller. Fig. 5 is a detail view on enlarged scale of a portion of the two disks of the controller illustrating the arrangement of the tracker and player pneumatic connections. Fig. 6 is a detail view of the valve for controlling the actuators of the controller.

In the accompanying drawings no attempt has been made to show in detail the various parts of a mechanical musical instrument which wind and re-wind the rolls or spools carrying the perforated music sheets and as illustrated in the diagram of Fig. 1, but a single player pneumatic is shown, it being understood, of course, that the number of player pneumatics depends entirely upon the number of tracker openings and that the controller device which forms the essence of the present invention is designed to control the tracker-ducts of whatsoever number with reference to a corresponding number of player pneumatics or other valve or motor devices which may be employed in a musical instrument and which it is desirable to control through the tracker ducts.

Referring to the diagram in Fig. 1, the numeral 1 indicates one tracker-board and 2 a second tracker-board wherein a single tracker opening 3 is shown in the tracker-board 1 and a single opening 4 is illustrated in the tracker-board 2.

The music roll or spool 5 for the tracker-board 1 is illustrated as being re-wound in the direction of the arrow appurtenant

thereto, it being presumed for the purpose of illustration that the music-sheet 6 has been played as it was wound upon the winding roll or spool 7 and is now being re-wound upon the spool 5. Therefore, its tracker-ducts are closed by the controller as hereinafter more fully described.

The music roll or spool 8 appurtenant to the tracker-board 2 is illustrated as bearing 10 a music sheet 9 which is being un-wound from the spool 8 and wound upon the spool 10 as it passes over the tracker-board 2. This music sheet 9 is in playing position and therefore the ducts of the tracker-board 15 2 are connected in operative playing position through the controller device with the player pneumatics.

The controller device for connecting and disconnecting the various ducts of the 20 tracker-boards 1 and 2 with the player pneumatics consists essentially of two disk-like members 11 and 12, each provided with a series of perforations which may be brought into and out of registering position 25 with each other. The disk 11 is as illustrated, secured to a standard or support 13 by a collar 14 while the disk 12 is free to oscillate or rotate upon a central bearing 15 which is concentric with a disk 11. This 30 disk 12 is held firmly against the face of the disk 11 by a spring 16 or other suitable device and is limited in its rotary or oscillatory movement with reference to the disk 11 by pins 17 fast in the disk 11 and projecting 35 through slots 18 concentrically arranged about the axis of the disk 12. These stop pins 17 preferably bear springs 19 which insure a good surface contact between the meeting faces of the disks 11 and 12.

40 The stationary disk 11 is provided with a series of concentric perforations 20, 21, 22, 23 from which project tubes 24 which serve as a convenient means for connecting the tracker tubes or ducts 25 of the tracker-board 1 and the tracker-ducts or tubes 26 of the tracker-board 2. The oscillatory disk 12 is also provided with a series of concentrically arranged perforations 27, 28, 29, 30 so arranged as to be brought into and out 45 of registering position with certain of the perforations of the stationary disk 11 upon partial rotation or oscillation. The perforations 27 to 30 inclusive are likewise connected with tubes 31 which serve as a convenient means for connecting with the ducts or tubes 32, 33 which lead to the player pneumatics. It will be observed that all of the perforations in the stationary disk 11 are arranged in concentric rows and in 50 radial lines while the series of perforations in the oscillatory disk 12 have the various perforations arranged in concentric rows with the alternate concentric rows of perforations arranged on the same radius. 55 Thus, when the oscillatory disk is in one

position, the perforations of the concentric rows 27 and 29 of the movable disk are in registering position with the perforations 20 and 22 of the stationary disk as illustrated in Fig. 5. The perforations 28 and 30 of the movable disk are then closed by the face of the stationary disk which is intermediate the radial lines of its perforations. When the oscillatory disk is shifted, the concentric rows or perforations 28 and 30 are brought into registering position with the perforations 22 and 23 of the stationary disk and thereupon the perforations 27 and 29 are closed by the stationary disk. With this arrangement, it is obvious that with 60 disks of comparatively small diameter, a great number of connections may be made and by a very slight oscillatory movement of the disks relatively to each other one or another of the series of openings may be 65 brought into registering position.

The oscillatory movement of the movable disk 12 may be secured in any desired manner. For the purpose of illustration, it is shown in the diagram of Fig. 1 as being 70 accomplished by small motors of the bellows type A, B, the movable board of each of these bellows being connected through suitable rods a', b' with the peripheral edge 75 of the movable disk.

To control the operation of the motors A and B, a valve C is employed in conjunction with the main bellows or source of power D of the instrument which, as illustrated, is actuated by a suitable motor. This bellows D through a suitable duct 34 is connected to an opening 35 in the stationary member of the valve C which stationary member has openings 36, 37 connecting through ducts 38, 39 with the motors A and B. The openings 36, 37 and their respective ducts are placed in communication either with the suction of the bellows D through the duct 34, 35 or with the atmosphere by a sliding valve member 40 which is provided with openings 41, 42 to the atmosphere and is also provided with a channel or duct 43 formed in its lower face and arranged to be brought into registering position with ports 44, 45 extending upwardly from the duct 35, said registration being dependent upon the position of the movable member 40.

As illustrated in the diagram of Fig. 1, the duct 38 is in communication with the main bellows D through the duct 34, passage 35, port 44 and ducts 43 and 36, thus collapsing the bellows A. The bellows B is open to atmosphere through the ducts 39, 37 and 42.

In Fig. 6, the parts are shown as just approaching the position above described and obviously if the movable member 40 is moved to the right, the reverse condition will attain and the bellows B will be col-

lapsed under the suction of the bellows D while the bellows A will be inflated upon being open to the atmosphere. This arrangement gives a positive movement to the 5 oscillatory disk 12.

The movement of the valve member 40 may be accomplished in any desired manner. As illustrated in the diagram, it is moved by a pivoted lever 46 to which it is connected 10 by a link 47. The lever 46 has at both ends spring-pressed latches, one latch 48 operating in conjunction with the music-roll 5 of the tracker 1, while a second latch 49 operates in conjunction with the music roll 8 15 of the tracker 2. As illustrated, as soon as the music sheet 9 has been un-wound from the music-roll 8, the end of the latch 49 will project into a notch 50 of the music roll and this will swing the lever 46 until the block 20 40 is shifted from the position shown in Fig. 1 toward the right to connect the duct 38 to the atmosphere and subject the duct 39 to the action of the suction of the bellows D.

It is to be understood, of course, that any 25 desired means may be used for shifting the movable disk 12, that above described being a convenient means for accomplishing the result.

The main suction D is connected with the 30 player pneumatics E by a duct 51 which communicates with a wind-chest 52, the action of which upon the player pneumatic 53 is controlled by a valve 54. This valve is mounted in a compartment 55 which is 35 normally open to the atmosphere through an opening 56 so that the pneumatic 53 will be expanded. It rests normally upon a valve opening 57 of the suction compartment 52.

40 As illustrated in the diagram, the tracker-ducks 26 of the tracker 2 are in communication with the ducts 33 of the player pneumatics while the tracker ducts 25 of the tracker 1 are closed with reference to the 45 ducts 32 of said player pneumatics. Therefore, the tracker-ducks 26 will actuate the player pneumatics E. As soon as an opening of the music sheet registers with a tracker-duct 26, atmospheric air is admitted 50 below a diaphragm 58 which under the suction of the chamber 52 will cause the valve 54 to rise. This movement will uncover the valve opening 57 and raise the diaphragm 58, subjecting the pneumatic 53 to the suction 55 of the chest 52 and cause it to collapse. The pneumatic 53 is, of course, connected in any suitable manner with the key or other sounding device of the instrument which it is desired to actuate. To re-seat the valve 60 54 after the closing of the tracker-duct, a bleed-hole 59 is provided which equalizes the pressure on both sides of the diaphragm 58 as soon as the tracker opening is closed.

A single player pneumatic and only two 65 tracker-connecting ducts 32, 33 are shown.

It is assumed, of course, that there will be a pair of tracker-ducks 32, 33 for each player pneumatic. Obviously, upon a shifting of the valve member 40, the tracker-ducks 25 of the oscillatory disk will be brought into 70 registering position with the player pneumatic ducts 32, 33 and thereupon the tracker 1 will be in playing position while the tracker 2 will be cut off.

Obviously, the details of the various mechanisms may be modified and changed to meet the exigencies of any particular case. While one form of accomplishing results is shown herein, it is merely illustrative for the purpose of showing a manner of actuating the 75 controlling device. It will be observed that in the form of controller herein shown, all of the connections may be readily made at a given point in the instrument and within a comparatively small space and that the relative movement of the disks to accomplish a coupling and un-coupling of the various ducts is very slight. With such a device as described, a maximum number of connections may be made within a minimum of 80 space and it will be observed that but four concentric rows of perforations are shown which occupy a comparatively small portion of the disks. Furthermore, the device is extremely simple to manufacture as the perforations may be arranged with great accuracy with a minimum of labor. It is preferred to make the disks of metal inasmuch as there is no liability of sticking and freezing of the parts due to variations in climatic 85 conditions.

There is a distinct advantage in utilizing the rotary disks and having the pneumatic motors A and B connected with the periphery thereof, one being inflated while the 90 other is exhausted as it is obvious from this construction that there is considerable leverage at the periphery of the disks which permits of certain and positive movement of the 95 oscillatory member.

100 What I claim as my invention and desire to secure by Letters Patent is:

1. A controlling device for pneumatic tracker-boards comprising two relatively movable disk-like members each provided with concentric rows of perforations and pneumatic connections, a portion of the perforations of one disk registering with those of the coöperating disk when the parts are 105 in one operative position.

2. A controlling device for pneumatic tracker-boards comprising two relatively movable disk-like members each provided with perforations and pneumatic connections, the perforations of one disk being arranged to be brought into and out of registering position with the perforations of the coöperating disk as the disks are oscillated 115 relatively to each other.

3. A controlling device for tracker-boards 120

- comprising two relatively movable disk-like members, one of said members having a series of concentrically arranged perforations arranged in radial lines about a common center, the other of said disks having a series of concentrically arranged perforations the alternate rows of which are arranged in radial lines about a common center.
4. A controller device for tracker-boards comprising a pair of disks, one of said disks being stationary and provided with concentric series of perforations arranged upon radial lines, the other of said disks having an oscillatory movement and being provided with concentric series of perforations, the alternate series being arranged upon radial lines and means for oscillating said disk.
5. In combination with a double set of tracker-board perforations and perforated music sheets, a stationary disk having a series of perforations connected with each set of ducts of the respective tracker-board perforations, a coöperating disk having perforations connected with the ducts of the player pneumatics and means for relatively oscillating said disks to bring the series of perforations corresponding to one tracker-board into and out of registering position with the series of perforations of the coöperating disk.
6. In combination with a double set of tracker-board perforations and perforated music sheets, a stationary disk having a series of perforations connected with each set of ducts of the respective tracker-board perforations, an oscillatory disk having perforations connected with the ducts of the player pneumatics and means under the control of the music sheet for oscillating said disk to bring its perforations into and out of registering position with either set of perforations of the stationary disk.
7. In combination with a tracker-board and perforated music sheet, a pair of perforated disks, one of said disks being stationary and having its perforations connected with the ducts of the tracker-board, the other of said disks having an oscillatory movement and having perforations connected with the player pneumatics and automatic means for oscillating said disk for moving its perforations into and out of registering position with reference to the perforations of the stationary disk.
8. A controller device for tracker-boards comprising two disk-like members, one of said members having concentric series of perforations, the alternate series connected respectively with the ducts of separate tracker-boards, an oscillatory disk having concentric series of perforations, the alternate series being connected with the player pneumatics of an instrument and means for oscillating said disk to connect the ducts of one tracker with the player pneumatics and close the ducts of the second tracker.
9. In a controlling device for tracker-boards comprising two relatively movable disk-like members, each provided with concentric rows of perforations, certain of the perforations of the movable disk arranged to register with certain of the perforations of the stationary disk upon partial rotation of said movable disk, two motor devices connected to substantially diametrically opposite edges of the movable disk and means for alternately actuating said motor devices.
10. In a controlling device for tracker-boards, two relatively movable disk-like members, each provided with concentric rows of perforations, certain of the perforations of one movable disk arranged to register with certain of the perforations of the coöperating disk upon partial relative rotation of said disks, two motor devices connected to opposite sides of the disk and means for alternately actuating said motor devices.
11. In a controlling device for tracker-boards, a plurality of tracker-boards each having music rolls and a traveling music sheet, two relatively movable disk-like members, each provided with concentric rows of perforations, certain of the perforations of one disk arranged to register with certain of the perforations of the coöperating disk upon partial relative rotation of said disks, a motor device for imparting relative rotation to the disks, a shiftable valve mechanism controlling said motor device and means operable from the music rolls for shifting said valve mechanism.
12. In a controlling device for tracker-boards, a plurality of tracker-boards each having music rolls and a traveling music sheet, two relatively movable disk-like members, each provided with concentric rows of perforations, certain of the perforations of disk arranged to register upon partial relative rotation of said disks, a motor device for imparting relative rotation to the disks, a shiftable valve mechanism controlling said motor device and connections between said valve mechanism and each set of music rolls whereby said valve is controlled.
